US0D1089271S

(12) **United States Design Patent** (10) **Patent No.:** **US D1,089,271 S**
(45) **Date of Patent:** ** *Aug. 19, 2025

(54) **MOBILE APPLICATION DEVELOPMENT DISPLAY SCREEN WITH GRAPHICAL USER INTERFACE**

(71) Applicant: **WAPP TECH CORP.**, Red Deer (CA)

(72) Inventor: **Donavan Paul Poulin**, Kelowna (CA)

(73) Assignee: **WAPP TECH CORP.**, Red Deer (CA)

(*) Notice: This patent is subject to a terminal disclaimer.

(**) Term: **15 Years**

(21) Appl. No.: **29/998,848**

(22) Filed: **Apr. 15, 2025**
